CLAIM

The ornamental design for an electrocardiogram recorder and charging stand in combination, as shown and described.

DESCRIPTION

FIG. 1 is a front perspective view of an electrocardiogram recorder and charging stand in combination showing our new design;

FIG. 2 is a front perspective view of the electrocardiogram recorder;

FIG. 3 is a front view of the electrocardiogram recorder;

FIG. 4 is a rear view of the electrocardiogram recorder;

FIG. 5 is a left side view of the electrocardiogram recorder;

FIG. 6 is a right side view of the electrocardiogram recorder;

FIG. 7 is a top plan view of the electrocardiogram recorder;

FIG. 8 is a bottom plan view of the electrocardiogram recorder, wherein the broken lines and the unshaded surfaces in FIG. 8 illustrate portions of the electrocardiogram recorder and charging stand in combination that form no part of the claimed design;

FIG. 9 is a front perspective view of the charging stand;

FIG. 10 is a front view of the charging stand;

FIG. 11 is a rear view of the charging stand;

FIG. 12 is a left side view of the charging stand;

FIG. 13 is a right side view of the charging stand;

FIG. 14 is a top plan view of the charging stand; and,

FIG. 15 is a bottom plan view of the charging stand, wherein the broken lines and the unshaded surfaces in FIG. 15

illustrate portions of the electrocardiogram recorder and charging stand in combination that form no part of the

claimed design.
